CLAIM

The ornamental design for a fiber-cement cutting tool, as shown and described.

DESCRIPTION

FIG. 1 is a top, left, front isometric view of an embodiment of a fiber-cement cutting tool showing our new design.

FIG. 2 is a left-side elevational view thereof.

FIG. 3 is a right-side elevational view thereof.

FIG. 4 is a front elevational view thereof; and,

FIG. 5 is a top plan view thereof.

The broken line portions of the disclosure are for illustration purposes only and form no part of the claimed design.
